UNITED STATES PATENT OFFICE

EDWARD S. CORNELL, JR., OF WATERTOWN, CONNECTICUT, ASSIGNOR TO THE CHASE COMPANIES, INCORPORATED, OF WATERBURY, CONNECTICUT, A CORPORATION

UNDERGROUND STORAGE-TANK INSTALLATION

Application filed October 10, 1930. Serial No. 487,748.

This invention relates to an improvement in underground storage-tank installations and particularly to underground fuel-oil storage-tank installations, though not so limited.

The main object of this invention is to provide an underground storage-tank installation which will insure the integrity of the pipe-connections with the tank proper despite the settling of the latter.

With the above and other objects in view as will appear from the following, my invention consists in an underground storage-tank installation characterized by a storage tank formed with an aperture; a water-tight slip-joint-fitting installed in the aperture of the said tank and provided with a through passage for the reception of a tube; and a continuous one-piece fluid-conducting tube extending through the said slip-fitting from the exterior to the interior of the said tank and having its periphery frictionally gripped by the said slip-fitting; whereby upon the settling of the tank, the said slip-fitting will move therewith and slip over the surface of the fluid-conducting tube without imposing a rupturing strain thereupon so that a continuous connection with the said tank is assured despite the said settling.

In the accompanying drawing:

Fig. 1 is a broken view in elevation of an underground storage-tank installation embodying my invention, the surrounding ground being shown in section and the tank proper broke away to facilitate illustration; and

Fig. 2 is a broken vertical central sectional view taken on the line 2—2 of Fig. 1, but on a larger scale.

For the illustration of my invention, I have herein shown only the suction or outlet-connection of an underground tank, but I wish to have it understood that my invention is also applicable to the inlet-connection, etc., thereof.

In carrying out my invention, as herein shown, I employ a cylindrical storage tank 10 which may be of any conventional type and which is buried in the usual manner beneath the surface of the ground 11.

The upper face of the periphery of the tank at 10 is struck up to form a boss 12 formed with an internally-threaded axial aperture 13 for the reception of an externally-threaded bushing 14 having a hexagonal boss 15 by means of which it may be threaded into place.

The bushing 14 is formed with an axial passage 16 extending completely through the same from top to bottom and having its upper end provided with internal threads 17 to receive the depending externally-threaded shank 18 of a body-member 19 of a slip-joint-fitting which may be of any approved type, but as herein shown, the body-member 19 is formed with an axially-arranged through-passage 20 and with an upstanding shank 21 provided with external threads 22 and having its top inner corner provided with a bevel 23 for co-action with the similarly-beveled under-face 24 of a compression-ring 25.

The upper face of the compression-ring 25 is formed with a bevel 26 extending in the opposite direction from the bevel 23 of its under-face and is arranged to be engaged by a beveled internal annular shoulder 27 of a compression-collar 28, the skirt 29 of which latter is formed with internal threads 30 for engagement with the external threads 22 of the upstanding shank 21 of the body-member 19.

Extending through the through-passage 20 in the body-member 19 is a fluid-conducting tube or pipe 31 which extends into the tank preferably to a point adjacent the bottom thereof to function as a suction-pipe and has its inner end provided with a strainer 32 which may be of any approved type. The tube 31 also extends through the compression-ring 25 and through the compression-collar 28 which two latter parts together with the body-member 19 constitute the slip-joint-fitting.

Preferably and as herein shown, the tube 31 is bent to form an integral horizontal reach 33, though I wish to have it understood that the said tube may be of relatively-short length and have its respective inner and outer ends coupled to separate tubes or pipes forming a continuation thereof.

In assembling my improved underground tank installation, it is preferable to first sleeve the slip-joint-fitting over the tube 31 together with the bushing 14 and then apply 5 the strainer 32 to the extreme lower end of the said tube. The inner end of the tube 31 carrying the strainer is now inserted through the aperture 13 in the tank and the bushing 14 screwed home. The threaded shank 18 of 10 the body-member 19 is threaded firmly into the bushing and the tube is adjusted vertically to bring the strainer 32 the proper distance above the bottom of the tank.

The compression-collar 28 is now screwed 15 down upon the upstanding shank 21 of the said body-member so as to compress the compression-ring 25 to a degree sufficient to cause its inner face to frictionally engage the periphery of the tube 31 to a degree sufficient to 20 exclude water and other foreign matter, but to permit the fitting to slide bodily over it in the event that the tank should settle.

Underground storage-tank installations have heretofore occasioned considerable trouble and expense for the reason that the settling of the tank with respect to the pipe or pipes connected therewith has occasioned ruptures in the pipes themselves or in the connecting fittings requiring, more often than 25 not, the removal of the overlying earth in order to effect repairs.

When my improved underground storage-tank installation is employed, the settling of the tank 10 with respect to the horizontal 30 reach 33 of the tube 31 which latter, it is to be remembered, is usually earthbound so as not to move with the tank, the settling referred to merely occasions the sliding of the slip-joint-fitting over the periphery of the 35 said tube 31 so that despite such settling, a continuous connection with the tank is assured.

It will be understood by those skilled in the art that my invention may assume varied 40 physical forms without departing from my inventive concept and I, therefore, do not limit myself to the specific embodiment herein chosen for illustration, but only as indicated in the appended claim.

50 I claim:

In an underground storage-tank installation, the combination with a storage tank buried beneath the surface of the ground and formed with an aperture; of a water-tight 55 slip-joint-fitting installed in the aperture in the said tank and provided with a through passage for the reception of a tube; a continuous one-piece fluid-conducting tube extending through the said slip-fitting from the exterior to the interior of the said tank and having its periphery frictionally gripped by the said slip-fitting; and an earth-bound horizontal fluid-duct leading laterally from the said fluid-conducting tube in spaced relationship 60 above the said storage-tank and having

earth or other filling interposed therebetween; whereby upon the settling of the tank the said slip-fitting will move therewith and slip over the surface of the fluid-conducting tube without imposing a rupturing strain thereupon or upon the earth-bound horizontal fluid-duct leading therefrom so that a continuous connection with said tank is assured despite the said settling.

In testimony whereof, I have signed this 75 specification.

EDWARD S. CORNELL, JR.
